TREATMENT OF HYDROCARBON OILS

Gustav Egloff, Chicago, Ill., assignor, by mesne assignments, to Universal Oil Products Company, Chicago, Ill., a corporation of Delaware

Application February 11, 1931, Serial No. 514,919
Renewed May 15, 1935

4 Claims. (Cl. 196—49)

This invention relates to the treatment of hydrocarbon oils and refers particularly to the conversion of relatively heavy hydrocarbon oils into substantial yields of lighter and more valuable products and reduction of the relatively heavy residual products of the conversion to coke or carbonaceous material.

Primarily the invention comprises subjecting hydrocarbon oil to conversion conditions whereby products both lighter and heavier than the charging stock are preferably produced and subjecting the relatively heavy residual products to reheat- ing and subsequent reduction under reduced pressure to substantially dry carbonaceous material.

As a feature of the invention the relatively heavy components of the vapors evolved by distillation of the residual oil from the cracking operation may be reheated either alone or together with residual liquid from the cracking system and are preferably introduced into the residuum redistilling zone to assist in the substantial devolatilization of the residual product of the system usually to effect its substantial reduction to coke or carbonaceous material.

The attached diagrammatic drawing illustrates one form of cracking system in which the principles of the present invention have been incorporated. The drawing and the following description will more clearly illustrate the novelty and

features of the present invention.

Raw oil charging stock may be supplied through line 1 and valve 2 to pump 3 to be fed through line 4, valve 5, preheating coil 6, line 7, valve 8 and line 9 into fractionator 10. Preheating coil 6 may be disposed within fractionator 11 and the raw oil fed therethrough may be preheated by indirect contact with the relatively hot vapors in this zone. Reflux condensate resulting from fractionation of the vapors and condensation of their relatively heavy components in fractionator 11 may pass therefrom through line 12 and valve 13 to pump 14 from which it may be fed through line 15 and may, if desired, be supplied, all or in part, through line 9 and valve 16 to fractionator 10 together with the preheated raw oil from line 7. The oil thus supplied to fractionator 10 may be preheated by direct contact with the relatively hot ascending vapors in this zone assisting their fractionation and passing together with their relatively heavy condensed components through line 17 and valve 18 to pump 19 from which the combined feed may be supplied through line 20 and valve 21 to heating element 22.

Heating element 22 may be located in any suitable form of furnace 23 and the oil supplied

thereto may be heated to the desired conversion temperature preferably under a substantial superatmospheric pressure. The heated oil may pass through line 24 and valve 25 to reaction chamber 26 also preferably maintained under substantial super-atmospheric pressure, which may be either substantially equalized with or lower than that employed in heating element 22. Separation of vapors and non-vaporized residual liquid may take place in chamber 26. The vapors may pass through line 27 and valve 28 to fractionator 10 from which their relatively heavy insufficiently converted components may be returned as condensate to heating element 22 for reconversion, as already described. The relatively light components of the fractionated vapors withdrawn from fractionator 10 through line 29 and valve 30, may be subjected to condensation and cooling in condenser 31, condensed distillate and uncondensable gas from which may pass through line 32 and valve 33 to be collected in receiver 34. Uncondensable gas may be released from receiver 34 through line 35 and valve 36. Distillate may be withdrawn through line 37 and valve 38. A portion of the distillate from receiver 34 may, if desired, be withdrawn through line 39 and valve 40 and recirculated by means of pump 41 through line 42 and valve 43 to fractionator 10 to assist fractionation in this zone.

Residual liquid withdrawn from reaction chamber 26 through line 44 may pass, all or in part, through valve 45, line 61, valve 62 and line 55 into residuum distilling and coking chamber 46. Any desired portion or all of the residual liquid instead of passing direct to chamber 46 may pass through line 47, valve 48, pump 49, line 50, valve 51 and line 15 to heating element 53 which may be located in any suitable form of furnace 54 and in which any desired quantity of additional heat may be supplied to the oil fed therethrough. Residual oil alone may, if desired, be supplied to heating element 53 or, if so desired, this product may be mixed prior to its introduction into the heating element with all or a portion of the reflux condensate from fractionator 11 which may be supplied from pump 14 through line 15 and valve 52.

Another method of operation embodied by the present invention permits reheating of substantially all or a portion of the reflux condensate from fractionator 11 in heating element 53 without the previous admixture of this product with any substantial quantity of residual liquid from chamber 26. In this latter case the residual liquid from chamber 26 may pass directly to cham-

ber 46, as already described. Heated oil from heating element 53 comprising either residual liquid or reflux condensate or residual liquid and reflux condensate, as the case may be, may pass 5 through line 55 and valve 56 mixing in this line with that portion, if any, of the residual liquid from chamber 26 fed directly through this line and passing therewith into chamber 46.

Chamber 46 is preferably maintained under 10 reduced pressure relative to that employed in chamber 26 and the heat supplied to the residual oil introduced into this zone, whether supplied directly to the residual oil in heating element 53 or supplied by admixture of the residual oil with 15 reheated reflux condensate or supplied partially in both manners is sufficient in any case to effect its redistillation and substantial reduction in chamber 46 to coke or carbonaceous material.

It will be understood that if desired two or 20 more chambers similar to chamber 46 may be employed either alternately or in parallel to permit prolonged operation of the process although for the sake of simplicity this arrangement is not illustrated in the drawing.

25 Chamber 46 may be provided with a drain line 63 and valve 64. Vapors from chamber 46 may pass through line 65 and valve 66 to fractionator 11 where their relatively heavy components may be condensed and returned, as already described, 30 either to fractionator 10 or to heating element 53 or in part to both. The relatively light components of the fractionated vapors from fractionator 6 may pass through line 67 and valve 68, to be subjected to condensation and cooling in condenser 69, products from which may pass through line 70 and valve 71 into receiver 72. Uncondensable gas may be released from receiver 72 through line 57 and valve 58. Distillate may be withdrawn through line 59 and valve 60.

40 Pressures employed within the system may range from subatmospheric to superatmospheric pressures as high as 2000 pounds per square inch or more. Substantially equalized pressure may be employed throughout the entire system or 45 differential pressures may be utilized between any of the various elements. As already stated reduced pressure relative to that employed in the reaction chamber of the cracking system is preferably utilized in the residuum redistilling or coking zone. Conversion temperatures employed 50 may range from 750° to 1200° F., more or less.

As a specific example of operating conditions which may be employed in the process of the apparatus above described, a 22-24° A. P. I. gravity fuel oil is subjected in the heating element 55 of the cracking system to a temperature of approximately 915° F. under a superatmospheric pressure of about 200 pounds per square inch. Succeeding portions of the cracking system comprising the reaction chamber, fractionator and the condensing and collecting equipment are maintained under a pressure substantially equalized with that employed in the heating element. A mixture of substantially all of the residual oil 60 from the reaction chamber and about one-half of the reflux condensate from the fractionator of the residuum distilling system is subjected in the reheating element to a temperature of approximately 875° F. under a superatmospheric pressure 65 of about 300 pounds per square inch and the reheated mixture is introduced into the residuum redistilling or coking chamber in which it is reduced to substantially dry coke or carbonaceous material.

70 75 The operation above outlined may yield ap-

proximately 65 percent of motor fuel having an anti-knock value approximately equivalent to a blend of 50 percent benzol and 50 percent Pennsylvania straight-run gasoline. About 12 percent of pressure distillate bottoms and approximately 15 percent of coke or carbonaceous material are also produced, the only other product being about 8 percent of fixed gas.

In general when oils of lighter gravity are processed, increased yields of liquid products and decreased yields of coke may be expected and vice-versa, this of course being also dependent, in part, upon the conversion temperatures and pressures employed. To generalize still further when the residual oil withdrawn from the reaction 15 chamber of the cracking system is a relatively light gravity clean product containing little suspending coke or carbonaceous material it may be passed through the reheating element without the prior admixture of reflux condensate from the 20 fractionator of the residuum distilling system. On the other hand, when this residual product is a relatively heavy material containing substantial amounts of suspended carbonaceous material and bottom settling it is preferably supplied directly to the coking chamber and additional heat for its reduction to coke may be supplied by reflux condensate from the fractionator 25 of the residuum distilling system which may be reheated alone.

30 I claim as my invention:

1. A hydrocarbon cracking process which comprises passing the charging oil in a restricted stream through a heating zone and heating the same therein to cracking temperature under 35 pressure, discharging the heated oil into a separating zone and separating the same therein into vapors and unvaporized oil, removing the unvaporized oil from the separating zone and passing a portion thereof directly to a flashing zone 40 maintained under lower pressure than the separating zone, removing the vapors from the flashing zone and dephlegmating the same to condense heavier fractions thereof, combining resultant reflux condensate with the remaining 45 portion of the unvaporized oil removed from the separating zone, passing the resultant mixture through a second heating zone maintained at conversion temperature, and then discharging the heated mixture into said flashing zone. 50

2. A process for cracking hydrocarbon oil comprising passing the oil through a heating coil wherein it is raised to cracking temperature, thence delivering the same to a high pressure reaction zone, passing residual products from 55 said high pressure reaction zone to a low pressure flash zone, diverting a portion of the residual products passing from said high pressure reaction zone to said low pressure flash still to and through a second heating coil and thence into 60 the low pressure flash still, separately taking off vapors from said reaction zone and said low pressure flash still, subjecting such vapors to fractionation and uniting a portion of the reflux condensate formed by fractionation of the 65 vapors with that portion of the residual oil passing through the second-mentioned heating coil.

3. A process for cracking hydrocarbon oil comprising passing the oil through a heating coil 70 wherein it is raised to cracking temperature, thence delivering the same to a high pressure reaction zone, passing residual products from said high pressure reaction zone to a low pressure flash zone, diverting a portion of the residual products 75

passing from said high pressure reaction zone to said low pressure flash still to and through a second heating coil and thence into the low pressure flash still, separately taking off vapors from said reaction zone and said low pressure flash still, subjecting such vapors to fractionation in heat exchange relation with charging oil for the process, and uniting a portion of the reflux condensate formed by fractionation of the vapors with that portion of the residual oil passing through the second mentioned heating coil.

4. A conversion process which comprises heating hydrocarbon oil to cracking temperature under pressure in a heating coil, separating the

heated products into vapors and unvaporized oil in a separating zone maintained under pressure, discharging a portion of said unvaporized oil directly from the separating zone into a low pressure flash still, passing another portion of said unvaporized oil from the separating zone through a second heating coil and thence into the low pressure flash still, fractionating the first-named vapors and the vapors from the flash still, passing resultant reflux condensate through the second heating coil together with said other portion of the unvaporized oil, and finally condensing the fractionated vapors.

GUSTAV EGLOFF.
